SHAPING FIXTURE

Albert F. Emrich, Valley Stream, N. Y.

Application March 30, 1945, Serial No. 585,753

1 Claim. (Cl. 153—80)

(Granted under the act of March 3, 1883, as
amended April 30, 1928; 370 O. G. 757)

This invention relates to a device for reshaping the inner arcuate surface of a cylinder.

The invention is described in connection with its use in reshaping bearing circles or azimuth circles which frequently are knocked off the compass stand during battle or otherwise misshapen through accident. It is noted that in the past when deformation occurred, the reshaping of the rings was accomplished by dropping or bouncing the rings on a work bench, floor, or other surface. In the case of sharp bends a raw hide hammer was used while the edge of the ring was held against the work bench.

One object of this invention is a device to reshape accurately inner cylindrical surfaces which have become deformed or distorted.

Another object of this invention is a device to reshape bearing circles and azimuth circles with such a high degree of accuracy that subsequent calibration of the circles will allow the use of these circles for navigational or piloting purposes.

Further objects and advantages of this invention, as well as its construction, arrangement and operation, will be apparent from the following description and claim in connection with the accompanying drawing, in which,

Figure 1 is a top plan view of the shaping fixture with portions broken away for clarity of illustration.

Figure 2 is a vertical section on the line 2—2 of Figure 1 and showing the operation of the device in connection with the reshaping of a bearing circle.

Figure 3 is a front view of the operating lever.

The shaping fixture has two generally semi-circular sections 10—10, each section 10 having a U shaped recess 11. When assembled together the combination of the two U shaped recesses 11—11 will form a generally square hollow for the reception of turnbuckle 12.

Turnbuckle 12 comprises a central knurled cylinder 13 and two threaded studs 14—15, extending therefrom. Stud 14 is left hand threaded while stud 15 is right hand threaded. Cylinder 13, also, has two bores 16—16 for the reception of operating lever 17.

Semi-circular sections 10—10 have threaded bores 18—18 to receive threaded studs 14—15.

Semi-circular sections 10—10, also, have bores 19—19 and 20—20 to receive pins 21—21. Bores 19—19 are of such size as to insure a snug fit with pins 21—21 while bores 20—20 are slightly larger than bores 19—19, to allow a relatively loose fit.

Figure 2 shows the shaping fixture in operation. In this instance bearing circle 22 is fitted on the shaping fixture, the knurled cylinder 13

is turned by hand until the semi-circular sections 10—10 are in contact with inner surface 23. The operating lever 17 is then inserted in either bore 16 and the semi-circular sections 10—10 are forced apart until the bearing circle 22 resumes the accurate contour necessary for its position on a compass stand.

It is to be understood that semi-circular sections 10—10 are accurately machined to insure 10 the precise shaping of the bearing circle 22.

It is to be understood that various modifications and changes may be made in this invention without departing from the spirit and scope thereof as set forth in the appended claim.

The invention described herein may be manufactured and used by or for the Government of the United States of America for governmental purposes without the payment of any royalties thereon or therefor.

What is claimed is:

A fixture for reshaping an internal cylindrical surface, said fixture comprising two generally semi-circular members, the said semi-circular members having their diameters closely parallel, a U shaped recess in each of said semi-circular members, the openings of said U shaped recesses being on the diameters of said semi-circular members, a left hand threaded bore in the base of the U of one of said recesses, a right hand threaded bore in the base of the U of the other of said recesses, a knurled cylinder within said recesses, said knurled cylinder having two threaded studs integral therewith, one of said threaded studs having a left hand thread and received in said left hand threaded bore, the other said stud having a right hand thread and received in said right hand threaded bore, said knurled cylinder having a plurality of bores, a lever, said lever being located in one of said knurled cylinder bores, a plurality of cylindrical apertures in each of said semi-circular members, said apertures being located between said recesses and the circumferences of said semi-circular members, said apertures being parallel 35 to said knurled cylinder and opening on the diameters of said semi-circular members, the apertures in one of said semi-circular members being in axial alignment with the apertures of the other of said semi-circular members, pins 40 extending between and within pairs of aligned apertures, the diameters of the apertures in one of said semi-circular members being slightly smaller than the diameters of the corresponding apertures in the other of said semi-circular members, whereby the pins are snugly received by one 45 set of apertures.

ALBERT F. EMRICH.
